UNITED STATES PATENT OFFICE.

JOHN C. VICKERS, OF EXPERIMENT, GEORGIA, ASSIGNOR TO DRAPER CORPORATION, OF HOPEDALE, MASSACHUSETTS, A CORPORATION OF MAINE.

WARP STOP MECHANISM FOR LOOMS.

Application filed April 3, 1928. Serial No. 266,914.

This invention relates to warp stop mechanisms for looms and is more particularly directed to warp stop mechanisms of the transversely movable detector bar type.

5 In warp stop mechanisms of the above-mentioned type the detector bar is given its movement transversely of the loom by means of actuating mechanism to which the bar is connected usually by a link. Where the link 10 is of the usual type now ordinarily made it is provided with a pivotal connection with the actuator at one end and an open socket at the opposite end which usually engages with a pin extending from the transversely 15 movable toothed detector bar. The link connection between the actuator and the toothed detector bar is thus readily detached from the detecting bar, which permits the latter to be moved into place in connection with 20 the drop wires and then connected to its actuating mechanism. On the other hand, it frequently happens during weaving or manipulation of the loom by the loom attendant that one or more of the detecting 25 bars may be accidentally detached from its connection with its actuating means, or, in other cases where the detachment has been made intentionally, the loom attendant may fail to connect the parts together, so that 30 during the weaving operation one or more of the banks of drop wires may not function to stop the loom on the breakage or undue slackness of a warp thread.

One of the important features of the present invention is to provide the connection 35 between the actuator and the detector bar with a lock which will act positively to hold the parts in their locked position so that they cannot become accidentally detached, 40 and when intentionally detached the lock itself will signal the fact that the parts are disconnected.

The invention and novel features thereof will best be made clear from the following 45 description and the accompanying drawings of one good form thereof.

In the drawings:

Fig. 1 is a view looking from the rear of the loom, showing one form of the trans- 50 versely movable detector bar warp stop mechanism containing the present invention, some of the parts being omitted;

Fig. 2 is an enlarged detail showing the detector and link connection between it and

its actuator in detached or unlocked position 55 and ready for assembly;

Fig. 3 is an enlarged side elevation of the connection between the detector bar and actuator, partly in section; and

Fig. 4 is a modified form of the lock.

The locking connection between the transversely movable detector bar and its actuator may be advantageously employed in any usual form of this type of warp stop mechanism, but, as indicated in Fig. 1 for illustrative purposes, the warp stop mechanism is of the general type shown in the patent to Davis and Johnson, No. 1,538,625, dated May 19, 1925.

As more fully described in the patent 70 mentioned, the warp stop mechanism comprises the end supports or brackets 1, one at each side of the loom, between which extend the warp rests or spacing bars 2. Mounted in a bracket 3 extending from one 75 of the side supports is the rock shaft 4 to which is connected the arm 5 which may be actuated through a link 6 and arm 7 from any convenient going part of the loom, as, for instance, a cam on the lower or cam 80 shaft, as usual. Mounted upon the rock shaft 4 is the rocker 8, of which there may be any suitable number corresponding to the numbers of banks of drop wires employed, and mounted upon the rocker 8 is the actuator 9 having pins 10 which rest in seats in the rocker 8 under the influence of a spring 11 normally acting as set forth and more fully described in the patent to which attention has been directed, to maintain the 90 actuator and rocker in operative relation and yet permit the actuator to come to rest when the transversely movable toothed detector bar to which it is connected is arrested on the occurrence of a warp fault. 95

Pivots mounted on the rocker at 12 is a finger 13 connected at 14 to the actuator, the construction being such that should the actuator be arrested while the rocker continues to move, the outer end portion of the 100 finger 13 will be depressed and act through a train of mechanism to effect loom stoppage. In the present instance of the invention, the finger 13 acts upon an arm 15 which rests upon the upper end portion of 105 plunger 16 associated with a flexible sheathed wire 17 which upon the occurrence of a warp fault is moved longitudinally, as more fully

explained in the Davis and Johnson patent, to effect loom stoppage. It is not necessary herein to further describe the particulars of the warp stop mechanism in detail since these are all fully described in said patent and the details of such mechanism form no essential part of the present invention.

Extending between the side brackets or supports 1 of the warp stop mechanism is the transversely movable detector bar 18, provided with a series of teeth 19, and associated with the movable detector bar is the relatively fixed toothed detector bar 20 which may be conveniently supported in the upper portion of the side brackets 1 of the warp stop mechanism, as more fully described in the above-mentioned patent, and as generally indicated at 21, Fig. 1.

In warp stop mechanisms of the transversely movable detector bar type, the movable detector bar is provided with a lug or projection for engagement with the link connection between the movable detector bar and actuator, and these parts may be variously contrived, but, as indicated in the present instance of the invention, the fixed detector bar has an open slot 22 in which may slide the pin or projection 23 secured to the movable detector bar 18.

In the present instance of the invention, the projection 23 is constituted as a pin having a head portion 24 and a shank portion 25, both of which engage the pin 23 and are held in place relative thereto by a nut 26. The details of this feature of the invention may be varied to suit conditions of use, but the above-described construction constitutes one good practical form thereof.

Pivotaly mounted upon the actuator 9 at 27 is a link member 28 preferably formed substantially as an inverted U-shaped member, as indicated in Figs. 2, 3 and 4, to pass above and straddle the upper portion of the adjacent side support or bracket 1. At its opposite end the link 28 is provided with an enlarged or open socket which may be appropriately formed in the downwardly extending portion 29 of the link. The enlarged or open socket 30 has a side portion 31 which, when the link is associated with the transversely movable detector bar, straddles the shank 25 of the projection or pin, with the result that the actuator will transmit to the movable detector bar its transverse detecting movement.

As hereinbefore indicated, the present invention contemplates locking means for locking the link in swinging engagement with the transversely movable detector bar, and as is indicated in Fig. 2, the locking member 33 is pivotally mounted upon the link or the downwardly extending member 29 thereof, at 32, and the downwardly extending arm 33 of the lock has an opening 34, the lower

wall 35 of which is adapted to pass below the pin or projection extending from the transversely movable detector bar when the lock is moved into its locking position, to thereby close the open end portion of the lock 30 in the link.

As indicated in Fig. 2, the downwardly extending portion 29 of the link is bifurcated, preferably throughout its entire length, as indicated at 36, and the lock is pivotally mounted to swing between the bifurcations thereof.

It is desirable when the lock is in locking position that it may be held in such position, and to this end the lock is provided with a weighted arm 37 which normally tends to move the lock into locking position and hold the lock in such position during weaving. When the lock is in locking position, as indicated in Fig. 1, the weighted portion 37 of the lock takes a determined position, preferably horizontal with respect to the straddling portion of the link 28, and when in unlocked position the weighted arm 37 will be raised, as indicated in Fig. 2, to thereby indicate to the loom attendant that the lock is not functioning and that before starting the loom the lock should be moved to its locked position.

From the construction thus far described it will be apparent that when the link 28 is operatively engaged with the transversely movable detector bar, it may be locked thereto by swinging movement of the lock into locking position, and yet it may be removed from locking position by reverse swinging movement of the lock, in order to permit the warp stop mechanism to be assembled or disassembled as the case may be.

As previously stated, the construction indicated by Fig. 4 shows a modification wherein the link 28 has its downwardly extending arm 39 provided with an open notch or socket 40 for engagement with the pin or projection extending from the movable detector bar 18, and pivotally mounted upon the link 28 is the locking member 41 having an inwardly extending end portion 42 adapted to engage in a suitable recess formed in the head 24 of the projection or pin. In order that the swinging lock 41 may not become accidentally detached from its locking position, the locking member 41 is formed as a spring arm the spring action of which normally tends to move the end 42 inwardly towards the downwardly extending member 39 of the link, the construction being such that by an appropriate outer pull upon the lower end of the locking member 41 it may be detached from its socket in the head 24 and then swung laterally into dotted line position, Fig. 4, in order to unlock the link from the movable detector bar.

Should the locking member 41 be swung to its unlocked position, as indicated by

dotted lines, Fig. 4, it will at once indicate to the loom attendant that the lock is in unlocked position and that probably, also, the link has not been secured to the transversely movable detector bar.

From the construction described it will be apparent that the link between the actuator and detector bar may be manually locked and unlocked by swinging movement of the lock upon the link and that the lock itself will normally be moved into locking position either by a weight or its equivalent, a spring, and that when unlocked it will visually indicate to the loom attendant that the parts are not in operative position.

What is claimed is:

1. In a warp stop mechanism for looms, the combination of a series of drop wires, a transversely movable detector bar having an actuating projection, an actuator, a connector between the actuator and detector bar having a notch for engagement with the projection, and a locking member mounted on the connector for movement relative thereto into engagement with the projection for positively locking the connector to the projection to insure detecting movement of the movable detector bar during the loom operation.

2. In a warp stop mechanism for looms, the combination of a series of drop wires, a transversely movable detector bar having an actuating projection, an actuator, a connector constituted as a link pivotally mounted on the actuator and having a notch for engagement with the actuating projection, and a locking member pivotally mounted on the link to swing into engagement with the actuating projection for positively locking the link to the projection.

3. In a warp stop mechanism for looms, the combination of a series of drop wires, a transversely movable toothed detector bar having a pin extending therefrom, an actuator, a link pivotally mounted at one end on the actuator and having a notch at its opposite end for engagement with said pin, and a locking member pivotally mounted on the link for swinging movement into and out of locking engagement with said pin to insure detecting movement of the detector bar during the loom operation.

4. In a warp stop mechanism for looms,

the combination of a series of drop wires, a transversely movable toothed detector bar, 55 an actuator therefor, and means for detachably locking the detector bar and actuator together, comprising a link mounted on one of said parts and having a notch, a projection on the other of said parts for engagement with said notch, a locking member carried by the link for swinging movement relatively thereto into and out of locking engagement with the said projection and an indicating signal associated with the locking 60 member to indicate the locked or unlocked position of the locking member.

5. In a warp stop mechanism for looms, the combination of a series of drop wires, a transversely movable toothed detector bar, an 70 actuator therefor, and means for detachably locking the detector bar and actuator together, comprising a link mounted on one of said parts and having a notch, a projection on the other of said parts for engagement 75 with said notch, and a locking member carried by the link for movement relative thereto into and out of locking engagement with the said projection and normally impelled 80 yieldingly into locking position.

6. In a warp stop mechanism for looms, the combination of a series of drop wires, a transversely movable toothed detector bar, an actuator therefor, and means for detachably locking the detector bar and actuator 85 together, comprising a link mounted on one of said parts and having a notch, a projection on the other of said parts for engagement with said notch, and a gravity actuated locking member carried by the link for 90 swinging movement relative thereto into and out of locking engagement with the said projection.

7. In a warp stop mechanism for looms, the combination of a series of drop wires, a 95 transversely movable toothed detector bar having a pin projection, an actuator therefor, a link pivotally mounted on the actuator and having an open notch for engagement with the pin projection, a lock pivotally mounted 100 on the link for engagement with the pin projection, and a weight normally acting to impel the lock into locking position.

In testimony whereof, I have signed my name to this specification.

JOHN C. VICKERS.
